UNITED STATES PATENT OFFICE

2,550,394

DISPOSABLE SYRINGE

Howard H. Young, Waukegan, Douglas A. Loper,
 Hubbard Woods, and Mack R. Fields, Liberty-
 ville, Ill., assignors to Abbott Laboratories,
 North Chicago, Ill., a corporation of Illinois

Application December 9, 1948, Serial No. 64,342

4 Claims. (Cl. 128—218)

1

Our invention relates to a unitary package and medicine injector especially effective in distributing and administering therapeutic agents of such characteristics that it is necessary or highly desirable that the attending physician put them into solution at or shortly before the time of use.

In the accompanying drawing,

Figure 1 is an elevation of an injector according to the invention, ready to effect an injection;

Figure 2 is an enlarged section of the equipment in the condition in which it leaves the place of manufacture or assembly;

Figure 3 is a plan view of the parts of Figure 2.

In the embodiment of the invention selected for illustration, the medicament is housed in a barrel 10 of transparent plastic, which barrel has oppositely directed finger grips 12 integrally unitized with it at its upper end. The lower closed end of the barrel has a central boss 14 in which a conventional cannula 16 is firmly embedded. The rubber piston 18 is at an intermediate point in the barrel and houses a charge of powdered medicament 20 in the space below it. It is provided with a downwardly opening central recess 22 to receive the upper end of the cannula 16. Imbedded in the piston is a threaded stud 23.

The space inside the cannula, in the packaged form, is substantially completely filled by a filler rod 24, the upper end of which projects above the upper end of the cannula and the lower end of which is bent around into a hook 26. The hook 26 is slightly resilient and has enough friction against the walls of the rod 28 to cause it to come out with the rod when the rod is removed. The entire exterior portions of the cannula 16 and the rod 24 are completely housed in the hollow piston rod 28. The piston rod has a saucer-shaped annular flange 30 at its upper end, which serves as a thumb rest or abutment in making an injection, and the piston rod has a snug fit on the boss 14. At its lower end it is hermetically closed at 32 and includes a short extension below the closure drilled and threaded at 34 to fit the stud 23. The entirety of the parts so far described, with the filling 20 in place, and all in completely sterile condition, may be wrapped in a sterile cellophane wrapper, indicated at 36.

When the medicine is to be administered, the user removes the cellophane wrapper 36, and if he touches the finger grips 12 and barrel 10 with unsterilized fingers at that time, no harm is done. He then pulls the piston rod 28 off the boss 14, pulls the filler 24 out of the rod and throws the filler away, and reassembles the piston rod in

2

the position of Figure 1. In this process he touches no part that needs to be kept sterile. In rare instances, if the filler 24 happens not to come out with the rod 28, it is quite easy for him to take hold of the hook 26 and withdraw the rod without touching the cannula. He then immerses the cannula in sterile water and by pulling the piston up in the barrel, he sucks a charge of water into the barrel to dissolve the medicament.

Finally, he may insert the cannula under the skin of the patient in any appropriate place and a slight withdrawal of the piston will aspirate blood if he has entered a blood vessel. After aspiration has indicated that the cannula end is properly placed, the medicament is forced in and the cannula withdrawn. After the medicament has been administered, the entire unit can be thrown away.

Others may readily adapt the invention for use under various conditions of service by employing one or more of the novel features disclosed. As at present advised with respect to the apparent scope of our invention, we desire to claim the following subject matter.

We claim:

1. A unitary disposable medicament syringe and package comprising, in combination: a barrel section having one end open and the other closed; outwardly extending grips on said barrel near the open end thereof; said closed end having a central axial boss; a cannula firmly imbedded in said boss and projecting outwardly; a filler rod obstructing and substantially filling said cannula and projecting beyond the outer end thereof; the projecting end of said filler rod being turned laterally to define a handle easy of access without touching said cannula; a tubular piston rod and housing having a closed end and an open end, said open end having a snug fit on said boss; an outwardly projecting flange around the open end of said piston rod defining a pressure head; said piston rod having a short extension beyond its closed end; a piston, when in package assembly lying intermediate the ends of said barrel to house a charge of medicament between itself and the closed end of said barrel; said piston and piston rod extension having threaded portions to connect said rod to said piston; a charge of medicament in said barrel below said piston; all the parts heretofore recited being in sterile condition; and a wrapper, proof against contamination, enclosing the entirety of said parts; whereby the user, after removing said wrapping can

remove said piston rod from said boss and assemble it with said piston, and remove said filler rod from said cannula, all without touching said cannula or any other part that needs to be kept sterile, until after contact with the patient is finished.

2. A unitary disposable medicament syringe and package comprising, in combination: a barrel section having one end open and the other closed; outwardly extending finger grips on said barrel near the open end thereof; said closed end having a central axial boss; a cannula firmly imbedded in said boss and projecting outwardly; a filler rod obstructing and substantially filling said cannula and projecting beyond the outer end thereof; the projecting end of said filler rod being turned laterally to define a handle easy of access without touching said cannula; a tubular piston rod and housing having a closed end and an open end, said open end having a snug fit on said boss; an outwardly projecting flange around the open end of said piston rod defining a pressure head; said piston rod having a short extension beyond its closed end; a piston, when in package assembly lying intermediate the ends of said barrel to house a charge of medicament between itself and the closed end of said barrel; said piston and piston rod extension having threaded portions to connect said rod to said piston; and a charge of medicament in said barrel below said piston; all the parts heretofore recited being in sterile condition.

3. In a unitary disposable medicament syringe, in combination: a barrel having one end closed and the other open; a boss extending axially outward from the closed end of said barrel; a cannula firmly imbedded in said boss; a filler rod substantially filling said cannula and projecting beyond both ends thereof; the outer projecting

end of said filler rod being bent around to define a handle easy of access without touching said cannula; a piston in said barrel; a tubular piston rod and housing having a closed end and an open end; said open end having a snug fit on said boss; said closed end and piston having co-operating portions shaped for screw thread assembly; said handle having a friction fit in said rod, whereby removal of said rod from said boss also removes said filler from said cannula, but whereby said filler may thereafter be removed from said rod conveniently.

4. In a medicament syringe, in combination: a barrel having one end closed and the other open; a boss extending axially outward from the closed end of said barrel; a cannula firmly imbedded in said boss; a filler rod substantially filling said cannula; said filler having a projecting end forming a handle thereof; a piston in said barrel; a tubular piston rod and housing having a closed end and an open end; said open end having a snug fit on said boss; said closed end and piston having co-operating portions shaped for connecting them together.
